DRIP RAIL ASSEMBLY FOR WINDOW

Robert B. Farnon, Louisville, and Stanley E. Rose, Lyndon, Ky., assignors to General Electric Company, a corporation of New York

Application May 29, 1957, Serial No. 662,499

1 Claim. (Cl. 20—70)

The present invention relates to a drip rail assembly for a window and more particularly to an assembly for draining water from the room side of a window to the outdoors while preventing reverse flow of air and water through the drain means due to high winds and driving rain on the outside.

Condensation which forms on the inside of windows when it is warm inside and cold outside sometimes creates a very difficult disposal problem. Modern construction materials, using metallic structural members for the window sash and other portions of the window, have greatly increased the amount of water which collects on the inside of these windows and in many cases the water drains onto the sill and from there onto the floor. Some installations provide a means for collecting this condensed moisture and draining it to the outdoors. However, most of these installations provide no means whereby cold air from the outside is prevented from entering the enclosure through the path provided for draining the water to the outside. In some cases, when there are high velocity winds and rain outdoors, these installations actually work in reverse and water from the driving rain flows back through the drain from the outside into the enclosure and drips onto the floor and carpets to damage these areas.

It is an object of the present invention to provide an improved drip rail assembly which will discharge condensate collecting therein even when high velocity winds and rains are directed onto the assembly from the outside.

It is another object of the present invention to provide a drip rail assembly for the removal of condensate collecting in a window which assembly substantially eliminates the possibility of cold air and water flowing from the outside back into the room through the drain means.

More specifically, it is an object of the present invention to provide a drip rail assembly which is mounted beneath a window for collecting condensate dripping therefrom and which is designed to produce a pressure differential in the drain passage for forcing the collected water to flow to the outside.

Further objects and advantages of this invention will become apparent as the following description proceeds and the features of novelty which characterize the invention will be pointed out with particularity in the claim annexed to and forming part of this specification.

In carrying out the objects of the present invention, there is provided a drip rail assembly having a longitudinal trough, disposed beneath the window on the inside portion of the assembly, which collects water falling from the window pane and other members of the window. The assembly contains a section carrying at least one passage therein having its ends exposed to the outdoors. The passage is designed to provide a gradually reducing cross sectional area from each of its ends to a point of minimum cross sectional area intermediate the ends whereby air currents flowing from one end of the passage to the other produce a pressure drop in the passage at the point of minimum cross sectional area. A

2

drain connection is provided which connects the trough portion of the assembly to the point of minimum cross sectional area in the passage whereby water collected within the trough is drawn from the room side of the assembly into the passage due to the reduced pressure in the passage at the point of minimum cross sectional area. Thereupon, the water is discharged to the outside along with air currents flowing through the passage.

For a better understanding of the invention, reference may be had to the accompanying drawings in which:

Fig. 1 is a cross sectional elevation view showing the drip rail assembly mounted in a window sill;

Fig. 2 is a plan view taken along line 2—2 of Fig. 1 and partially broken away to show the drain passage; and

Fig. 3 is a plan view similar to Fig. 2 taken along line 3—3 of Fig. 1 and showing the baffle arrangement of the drip rail assembly.

Referring to Fig. 1, there is shown the drip rail assembly of the present invention mounted upon a window sill 2 and arranged beneath a glass window pane 3 contained in a closure panel having a metallic member 4 forming the outer boundary of the panel. This type of closure panel is sometimes used in the window of office buildings to close off a portion of the window next to an air conditioner mounted through one side of the window. The drip rail assembly comprises a longitudinal member 6 having a C-shaped or channel-shaped cross section with the open portion 7 of the member facing the outside. Means in the form of an upwardly extending flange 8 is provided to form a seal between the drip rail assembly and the window or closure panel. More specifically, the flange 8 rises from the upper surface or leg 9 of the C-shaped section 6 and has attached thereto, for the length of the rail, a resilient sealing gasket 11 which abuts the lower portion of the closure panel member 4 thereby sealing the lower boundary of the window panel from the outdoor elements.

In order to collect moisture and water condensing on the window pane 3 and on the metallic closure panel member 4 a trough 12 is provided beneath these members. The trough is formed by a portion of the upper surface or leg 9 of the C-shaped section 6 and the flange 13, which extends the length of the C-shaped member and is attached to the upper corner thereof. The flange 13 extends into the room a slight distance and is supported by a leg 14 resting upon the window sill 2. The flange 13 is slanted slightly upwardly toward the room side of the trough thereby causing water or moisture collecting in the trough to flow downwardly and collect against the upwardly extending sealing flange 8.

As may be more clearly seen in Figs. 2 and 3, the open portion 7 of the C-shaped section 6 is divided into a series of passageways by a plurality of baffles 16 which are permanently assembled into the open portion 7 of the C-shaped section 6. Thus, referring to Fig. 3, baffle 16, which is formed of a long member of rectangular cross section having a slight angular bend 17 intermediate the ends 18 thereof, is inserted into the open portion 7 of the C-shaped section with the bend 17 substantially closer to the base or web portion 10 of the C-shaped member than are the ends 18 of the baffle. It can be seen that each of the baffles 16 form a passage 19 having its ends or openings 21 facing the outside. Each passage has a gradually reducing cross sectional area from its ends thereof to a point of minimum cross sectional area 22 where the bend 17 of the baffle 16 lies closely adjacent the base 10 of the C-shaped section. Thus, by virtue of the configuration or slope of the baffles 17, they, together with the base 10 and the upper and lower legs 9 and 9a respectively of the C-shaped section, form a plurality of converging-diverging passages in the open portion 7 of the section.

It should be noted that, for manufacturing reasons, it was found more economical to make the baffles 16 as separate members and assemble them later rather than make them as an integral part of the C-shaped section 6. However, there is no reason, other than manufacturing economics, why these members should not be an integral part of the section 6.

By means of the ends or openings 21 in the passages outside air currents are directed into the passages 19 and forced to flow therethrough. For example, as may be seen in Fig. 3, outdoor air blowing from the lower right side will enter the lower end or opening 21 at an angle and flow through the passages 19 as indicated by the arrows. Depending upon the direction of the wind or air currents, air will be trapped by the passages 19 and will flow through the converging-diverging passages in one direction or another. As a result of this particular construction the absolute pressure of the air flowing within the passages rises and falls. Specifically, at the narrowest portion 22 of the passages the pressure is often below atmospheric because the constriction in the passage at this point promotes an increase in the velocity of air flow which in turn creates a pressure drop at this point.

In order to dispose of water collecting in the trough 12, a series of connectors or drain passages 23 are provided which connect the trough 12 with the air passages 19 at the points of minimum cross sectional area 22. Due to the reduced pressure in the air passage 19 at the narrow portion 22, a suction effect is produced in the drain passage 23, which causes air from within the enclosure or room to be drawn into the passage 19 and flow from within the room to the outside. Thus, any air flow through the drain passage 23 will be from the inside of the room to the outside. Further, since the trough portion 12 also collects the water formed on the room side, the water is also drawn through the passages 23 and discharged outside with the air. By this means water collected on the room side is forcefully removed to the outside.

Obviously, the suction effect is greater on those days when a greater air flow is experienced in the passages 19. Thus, during high winds or driving rains, when many draining arrangements have a tendency to flow in reverse, the drain arrangement of the present invention becomes even more effective. In a tested installation of the drip rail assembly, in which four baffles 16 were used, thereby forming four venturi-like passages 19, and having drain connections or holes 23 of $\frac{3}{16}$ inch in diameter leading from the trough 12 to the minimum cross sectional area 22 of the passages 19, it was found that good pressure characteristics were obtained at all angles of approach to the drip rail assembly for the air currents on the outside. Even those angles of approach directly normal to the assembly provided a sufficient drop in absolute pressure at the point of minimum cross sectional area 22 to produce effective operation. This is attributed to up-drafts and down-drafts which occur when the air flows directly normal to the building or house.

It should be noted that the drip rail assembly of the present invention could obviously be made an integral part of the window itself. Thus the drip rail could form

the window sill of a metallic window construction and the sealing arrangements could be so designed that the window could be opened or closed in the same manner as normally provided in a window having the conventional type window sill. The C-shaped section and the trough would be arranged substantially as described above.

By the present invention there has been provided an effective means for removing moisture and condensation which forms on the window and its associated parts due to cold temperatures on the outside and higher temperature in the room or enclosure. Moreover this means also prevents the introduction of drafts into the enclosure from the outside through the drain passages provided for removing the condensate from within the enclosure. The invention also works particularly well under conditions wherein there is a driving wind blowing against the assembly, since the draining operation of the assembly depends on a venturi-like effect produced by the wind in addition to gravitational forces which effect drainage of the water during those times when the wind is not blowing.

While there has been shown and described a specific embodiment of this invention, it is to be understood that the invention is not limited to the particular form shown and described and it is intended by the appended claim to cover all such modifications within the true spirit and scope of the invention.

What we claim as new and desire to secure by Letters of Patent of the United States is:

A drip rail assembly for collecting and disposing of condensate formed on the inside of a window comprising means for supporting said assembly on a window sill, an upwardly extending flange in sealing engagement with the lower portion of said window, a trough portion disposed on the room side of said flange and extending below said window for collecting moisture falling therefrom, a longitudinal section disposed substantially below said flange of generally channel-shaped cross section with said open portion of said section exposed to the outside, at least one baffle assembled in the open portion of said channel-shaped section, said baffle being angled inwardly from its extremities toward the web of said channel-shaped section and cooperating with said channel-shaped section to form a horizontally extending air passage with its ends exposed to the outside, said angled portion of said baffle causing said passage to gradually reduce in cross sectional area from the ends thereof to a point of minimum cross sectional area intermediate the ends whereby air currents flowing from one end of said passage to said other end produce a pressure drop in said passage at said point of minimum cross sectional area and a drain passage connecting said trough portion with said air passage only at said point of said minimum cross sectional area whereby water is drawn from said trough by said reduced pressure in said passage at said point of minimum cross sectional area and discharged to the outside with air currents flowing through said passage.
